WALLPAPER TEMPLATE FOR A COMBINATION DOUBLE OUTLET AND ELECTRICAL SWITCH PLATE

John Douglass Black, 9332 Ambassador Drive,
Westminster, Calif. 92683

Filed Nov. 22, 1974, Ser. No. 526,142

Term of patent 14 years

Int. Cl. D8—09; D19—08
U.S. Cl. D10—64

FIG. 1

FIG. 2

FIG. 4

FIG. 3

FIG. 5

FIG. 1 is an isometric view of my new wallpaper template for a combination double outlet and electrical switch plate;

FIG. 2 is a bottom view thereof;

FIG. 3 is a side view thereof;

FIG. 4 is a top view thereof; and

FIG. 5 is an end view thereof.

I claim:

The ornamental design for a wallpaper template for a combination double outlet and electrical switch plate, as shown and described.
